TYPE LOCK FOR MAILING GALLEYS

Ralph B. Orr, Logansport, Ind.

Application October 31, 1947, Serial No. 783,267

4 Claims. (Cl. 276—41)

1

This invention relates generally to the art of typesetting, and has for its principal object the provision of a locking device for type matter stored in galleys. Certain specific features of my device make it particularly adaptable to the locking of type matter in so-called mailing galleys; that is, type matter consisting of the names and addresses of subscribers to a newspaper, for example. Matter of this type is generally stored more or less permanently in relatively narrow galleys within which the slugs or pieces of type remain unchanged over long periods, but in which corrections, changes of address or the like must occasionally be made.

It is, therefore, also an object of the invention to provide a galley lock of the general type indicated above which will firmly retain within a galley pieces of type matter of the above description, more particularly in the form of individual line units or slugs, but which will be capable of yielding sufficiently to enable one or more slugs to be removed from the assembly and replaced by one or more corrected slugs, without requiring any repositioning of the locking device.

I am well aware that it has often been proposed to provide a galley end-lock for type matter to replace the usual cumbersome weights or other furniture used to fill out vacant space in galleys. Some of these, indeed, have utilized strips of resilient material in order to retain the locking device in position by endwise pressure against side-walls of the galley, but in all such cases, so far as I am aware, the purpose, intent and effect of such locks has been to achieve absolute rigidity in the direction of the length of the galley. The use of such locks thus inhibits the making of changes or corrections except by removing the locking device, and hence renders them impractical for use in galleys of the type with which I am principally concerned.

A further object of the invention is to provide a structure having the above advantages but which can be manufactured at a very low cost, and which is simple and foolproof in operation. Also, a preferred construction herein to be disclosed provides for reversability of the assembly for the most efficient use thereof by persons who are either right or left-handed.

My invention completely eliminates the need for reglets or blocks often used to clamp in place type matter in galleys, and provides for a continuous variation in adjustment to accommodate any length of column without necessitating the tedious insertion of properly dimensioned blocks, the use of thumb screw clamps or the like ex-

2

pedients heretofore employed for this general purpose.

The above and other objects and advantages of the invention will best be understood by reference to the following detailed description of a preferred embodiment thereof, taken in connection with the accompanying drawings, in which:

Fig. 1 is a perspective view of a mailing galley containing a number of slugs of type matter held in place by one embodiment of the invention.

Fig. 2 is a plan view of a lock in accordance with the invention.

Fig. 3 is an elevation thereof.

Fig. 4 is a sectional view taken along line 4—4 of Fig. 2, and

Fig. 5 is a partial plan view of the structure of Fig. 1, showing the manner of removal of a type slug.

Referring now to Fig. 1 of the drawing, there is illustrated a mailing galley 10 comprising an elongated rectangular container having parallel side walls 12 and 14, and containing a plurality of slugs 16 of type matter, such as names and addresses of subscribers to a publication. The mailing galley 10, as is usual in this art, is narrower than galleys used for ordinary columnar matter, and may preferably have a width of about 2 inches, whereas a standard size single-column galley would have a width of three inches, a two-column galley five inches, and so on. Moreover, the mailing galley 10 is usually if not always closed at both ends, whereas the other standard galleys are open at one end.

The improved galley lock in accordance with my invention is illustrated in Figs. 1 to 4 as comprising a thin yet stiff length 18 of resilient material, such as spring steel, which in its normal or unstressed condition is bowed along a major portion of its length, for example on an arc having a radius of about 3 inches. At one end, however, which is the right end in Fig. 1, a minor portion 20 of the length of the strip 18 is reversely bent so as to extend at an angle of about 20° to the general direction of the strip 18.

The above described shape of strip 18 provides a certain degree of resilience in the direction of the length of galley 10 when the strip is wedged into place between the opposed side walls 12 and 14 of said galley, as otherwise, if a simple bowed strip were used, the strip would form a structural arch across the galley and any force exerted by the type matter upon said strip would meet a rigid resistance as will be apparent to anyone familiar with the mechanics of arches.

In order to provide a contact between strip 18

and the end slug of type in the galley, there is secured to strip 18, approximately at its mid-point, a relatively rigid and unyielding bar or contact piece 22 here shown as a slightly dished piece of metal in order to provide spaced contact points on the end slug. Bar or piece 22 is preferably slidably secured to strip 18 as by being riveted to a clip 24 whose ends are folded about the upper and lower edges of the strip, and bar 22 is dimensioned so as to slide freely within the walls 12 and 14 of the galley 10 when the locking device is inserted, whereby to contact and press upon the end slug without interference from the walls. The purpose of making clip 24 slidable on strip 18 is to permit the bar 22 to be assembled with minor portion 29 of the strip 18 lying at either end of the assembly, for greater convenience of users who may be left-handed.

In use, the locking device is simply slid up against the end slug of type with sufficient pressure to wedge it firmly in place between the galley side walls, whereupon it will secure the type slugs firmly in an upright printing position from which they will not be dislodged by any normal or even rough handling. Thus the use of reglets or wooden or metal blocks to fill out the galley, or thumb screws or the like at the end of the galley is rendered unnecessary, and at the same time much greater convenience and speed in locking the type is accomplished.

When it is desired to replace a line or slug, for example to change a name or address, it is unnecessary to release the lock. A make-up rule 26 or similar thin rigid tool is merely applied at the end of the slug, and by prying up the old slug is removed and the new one inserted, while the locking device springs lengthwise of the galley sufficiently to permit this action. When the makeup rule is removed, the lock springs back and forces the type back into place ready for use.

If circumstances require the removal of one or more slugs, or the addition of any, the lock is released by inserting a makeup rule or the like behind the curved end of the strip 18 and exerting pressure, whereupon the lock may be removed, the type slugs changed, and the lock replaced as described above.

Since the parts of my improved lock are few and simple, the device can be manufactured at low cost, and will permit substantial savings in time and effort in handling mailing-galley matter of this kind.

Having disclosed a preferred embodiment of my invention, I wish it to be understood that changes and alterations may be made in the specific structure chosen for illustration without

departing from the spirit of my invention as defined in the appended claims.

I claim:

- 5 1. A resilient end lock for supporting type matter within a mailing galley having substantially parallel side walls, comprising a stiff resilient strip of material shaped to provide a major portion of its length bowed in one direction longitudinally of the strip, a minor portion adjacent one end being reversely bowed for a short distance to provide galley-wall contacting end portions of said strip directed in opposite directions when the strip is wedged between side walls of a galley, and a rigid type-contacting member of 10 less length than said strip affixed to the strip only adjacent approximately the center of the strip and lying on the convex side of said major portion, said strip being sufficiently stiff to maintain said lock abutted firmly against type matter 15 in said galley, but sufficiently resilient in a direction lengthwise of said galley to enable a line of type matter to be removed and replaced without disturbing the locking engagement between said strip and said walls.
- 20 2. A resilient end lock for supporting type matter within a galley of the type having substantially parallel side walls, comprising a stiff resilient strip of material bowed for a major portion of its length in one direction, and bent in the 25 opposite direction for a minor portion of its length and a rigid type-contacting member removably secured to said strip only adjacent approximately the center of the strip on the convex side of the major portion thereof.
- 30 3. A galley lock for type galleys comprising a springy member normally bowed along most of its length in one sense and bowed at one end in a reverse sense, and normally having an overall length slightly in excess of the width of a galley 35 with which it is to be used, whereby said member when wedged between walls of a galley is held against bodily movement but may be flexed longitudinally of said galley at an intermediate portion of its length.
- 40 4. The invention of claim 3, and a rigid type-contacting bar connected to said member intermediate its length.
